POWER OPERATED REGULATING MECHANISM
 Jakob Stelzer, Raunheim (Main), Germany, assignor to
 H. T. Golde G.m.b.H. & Co., K.G., Frankfurt am
 Main, Germany

Filed Apr. 5, 1963, Ser. No. 270,833
 5 Claims. (Cl. 268—124)

This invention relates to power operated window regulating mechanism and more particularly to a novel drive mechanism for opening and closing sliding windows in, for example, motor cars and the like vehicles.

This is a continuation-in-part of applicant's copending application Serial No. 836,551, filed August 27, 1959, for window regulating mechanism, now abandoned.

In low built modern motor cars with vertically and/or longitudinally curved walls and door panels the space between the outer and the inner panels is restricted especially with the sliding window pane lowered. Therefore, serious difficulties are encountered in providing window regulating mechanisms which can be installed in said space without interfering with the path of the sliding window pane, the more as in the case of a vertically curved window pane its correspondingly curved sliding path may involve additional restrictions.

According to a heretofore known construction a threaded flexible cable connected to the lower edge of a sliding window pane and axially movable in a tubular guide is in threaded engagement with the hollow shaft of an electric motor for lowering and raising this pane by respective rotation of the motor shaft. The motor accordingly must extend radially with regard to the flexible cable. If sufficient space to position the motor below the window path is not available, it may be possible to find a suitable place for the motor in greater distance of the window path which, of course, requires a considerably greater length of the flexible cable and its tubular guide, resulting in increased friction when the cable is moving to operate the sliding pane.

It is an object of this invention to provide a regulating mechanism for sliding windows in motor cars and the like with a cable in a tubular guide wherein rotating means, for instance an electric motor, for actuating said cable may be located at any place distant from the window path without necessitating a greater length of tubular guide, thereby minimizing friction losses.

It is a further object of the invention to provide a power operated regulating mechanism of the aforementioned type wherein an inexpensive commercial electric motor, for instance of the type conventionally used for operating windshield wipers, may be used for actuating the flexible cable.

It is a further object of the invention to provide a regulating mechanism for sliding windows in motor cars which may be installed in any type of vehicle after its completion by the manufacturer and regardless of the space available.

It is also an object of the invention to provide a window regulating mechanism of a simple and inexpensive construction, which can be installed with a minimum of work.

A still further object of the invention is to provide a novel tubular guide by which operating noises and wear are minimized.

Further objects and advantages of the invention will be apparent from the detailed description and other matter in the specification following below.

For better understanding of the invention reference is made to the accompanying drawings and descriptive matter in which there are illustrated and described some preferred embodiments of the invention.

In the drawings:

FIG. 1 is a schematic front elevation of a first embodiment

2

ment of a window regulating mechanism constructed in accordance with the invention;

FIG. 2 is a section taken on line II—II of FIG. 1;

FIG. 3 is a schematic side view illustrating the arrangement of a second embodiment of a window regulating mechanism constructed in accordance with the invention as built into an automobile door;

FIG. 4 is a section taken on line IV—IV of FIG. 3;

FIG. 5 is a section similar to the section shown in FIG. 3 illustrating the mechanism according to the second embodiment as built into an automobile door with a curved window pane;

FIG. 6 is a section taken on line VI—VI of FIG. 3;

FIG. 7 shows a detail of the regulating mechanism according to FIG. 3 on an enlarged scale;

FIG. 8 is a section on line VIII—VIII of FIG. 7;

FIG. 9 shows a detail as viewed in the direction of arrows IX—IX of FIG. 7; and

FIG. 10 is a schematic view similar to that of FIG. 3 showing still another embodiment of the regulating mechanism according to the invention as built into an automobile door.

Referring to the drawings and in particular to FIGS. 1 and 2, there is shown a flat window pane 7 positioned for up and down movement relative to and within a pair of guide channels 8 as conventionally mounted in an opening of a car door. A channel-shaped mounting 6 connected to a supporting angle 5 as illustrated in FIGS. 1 and 2 is designed to support the window pane 7 at about the center of its bottom edge for vertical movement. A tubular guide 2 is positioned in a plane parallel and offset relative to the path of movement of window pane 7. The guide 2 is adapted to be fixed to the inner panel of an automobile door, for example in a manner explained below in connection with FIGS. 3 and 4, and is provided with a vertical slot 3 which extends at least the length of travel of the window pane 7.

The supporting angle 5 is provided and rigid with a bracket 4 extending into the slot 3 for connection with a flexible cable 1 which extends below the end of guide 2 into a gear housing 9 and a curved guide extension 2a. The flexible cable is rigid to axial forces and guided parallel to the sliding path of window pane 7 within guide 2 which fits closely around its periphery. Furthermore, the cable is constructed of helical strands which may engage a pinion in a manner similar to a rack or it may be provided with a specially threaded profile for that purpose.

The gear housing 9 connects the tubular guides 2 and 2a by means of a pair of threaded nuts 14 which align the guide 2 with the gear housing and a portion of the guide 2a. While one extreme end of the flexible cable 1 is secured to the bracket 4 for movement thereof, the other end is allowed to move loosely within the guide 2a where it may be conveniently kept out of contact with other mechanisms in the automobile door. A pinion gear 10 mounted within the housing 9 positively engages the flexible cable 1 within the housing and also meshes with a second flexible cable 11 similar to the flexible cable 1. One end portion 11a of the flexible cable 11 is journaled in a bearing 15 fixed to the housing 9 while the opposite end is connected to the shaft of a reversible electric motor 12 through a resilient coupling 13.

It is to be noted that pinion 10 meshes tangentially with both cables 1 and 11 and that in operation with pinion 10 rotating cable 11 is also rotating while cable 1 is shifted axially because rotation thereof is prevented by the bracket 4, which is fixed to the cable 1 and guided by the slot 3 of the guide 2. The motor may be carried by the housing 9 by means of suitable brackets 16 fixed to the motor and to the housing. The position of motor 12 is not critical but may be chosen in

accordance with the space available, because the torque of motor 12 is always positively transmitted to the pinion 10 by the second cable 11.

The speed of motor 12 is substantially reduced by the worm 11 which may be driven in either direction depending upon the control of the motor 12. Thus, advantageously relative slow rotary motion of the pinion 10 within the housing 9 and translatory longitudinal motion of the flexible cable 1 within the tubular guides 2 and 2a and the housing 9 is accomplished even with a small high speed motor of the type conventionally used for operating windshield wipers. The bracket 4 which is secured to the upper end of the cable 1 moves the window 7 vertically in conformity with arrow A within the guide channels 8. The tubular guides 2 and 2a may have any shape adaptable with the space available therefore and as permitted by the flexibility of the cable 1, since only the slotted portion of guide 2 must be parallel to the window path.

In the drawings, the entire cable 1 has a wormlike outer surface. It will be realized, however, that an ordinary cable with a smooth surface may be employed, provided that a wormlike portion is interpositioned in the region where the pinion 10 engages the cable. The same applies to cable 11 whereof only that portion engaging the pinion must be provided with gear engagement means.

In the second embodiment shown in FIGS. 3 to 9, wherein similar parts are provided with the same reference numerals as in FIGS. 1 and 2, an automobile door is shown as viewed from outside having an outer panel 20, a generally triangular window 22 and a sliding window pane 7 positioned for up and down movement relative to and within a pair of guide channels 8.

A mounting 6 supporting pane 7 is rigidly connected to a supporting angle 5 connected to a bracket 4 which bracket in turn is rigidly fixed to the upper end of a first length 28 of a flexible cable having a worm-like profile and being guided in a longitudinally slotted tubular guide 26. Guide 26 extends through a housing 30 wherein a pinion 34 is rotatably mounted and tangentially engaged by the cable 28. Pinion 34 is further tangentially engaged by a second length 40 of flexible cable similar to the first length 28. Cable 40 is journalled in the housing 30 and connected for rotation to the shaft of an electric motor 42. Motor 42 is rigidly mounted to the inner panel 44 of the automobile door in a position spaced from cable 28 and housing 30, which latter is also fixed to the panel 44 (see FIG. 4). A tube 46 of flexible material, for instance plastic, is connected to the bottom end of guide 26 for receiving and protecting the free end of the axially moving cable 28 when the pane 7 is lowered.

As shown in greater detail in FIGS. 7 and 8, housing 30 comprises a rear part 31 and a front part 32 rigidly connected together and to the inner door panel 44 by suitable fasteners, for instance screw means 36. The rear and the front part are shaped to provide passages for the respective portions of cables 28 and 40 adjacent the pinion 34. Integral bosses 35 of pinion 34 are rotatably received in aligned circular bores in the rear and front parts 31 and 32 of housing 30.

One end 41 of cable length 40 is journalled in a bearing 48 fixed to the housing 30. The opposite end 47 is resiliently coupled to a bushing 49 by means of a block 50 of elastic material, for instance synthetic rubber. A suitably profiled shaft end 51 of the shaft of motor 42 is received in an inner bore of bushing 49 which bore is profiled to prevent relative rotation between shaft end 51 and bushing 49. Accordingly, with the motor shaft rotating shaft end 51 will cause rotation of cable length 40 via the bushing 49 and the resilient coupling 50 vulcanized to cable end 47. Rotation of cable length 40 will cause rotation of pinion 34 and rotation of pinion 34 will cause axial movement of cable length 28 within the tubular guide 26, whereby rotation of

cable length 28 is prevented by the rigid connection between the cable 28 and the bracket 4, which latter is guided in the longitudinal slot 27 (FIG. 6) of guide 26.

As shown in FIG. 6, the longitudinal edges 29 defining the slot 27, which slot extends over the whole length of guide 26, are rounded, thereby minimizing friction and wear when the bracket 4 is travelling in the slot and also avoiding noises which might occur with a roughly cut slot.

To obtain the desired shape of slot with rounded edges, guide 26 is made from sheet metal strip with rounded longitudinal edges by bending such strip to obtain the desired circular cross section with a longitudinal gap providing the guiding slot 27.

The tubular guide 26 is longitudinally shaped in accordance with and parallel to the sliding path of the window pane 7 and is rigidly fixed near its upper end to the inner door panel 44 by a suitable bracket 52, while its lower end portion is clamped between the rear and front parts 31 and 32 of the housing 30. As shown in FIG. 7, a recess 26a, provided in guide 26, enables the teeth of pinion 34 to engage the worm-like profile 28a of cable 28.

For better understanding the device according to FIG. 7 is shown on an enlarged scale, as compared with its actual dimensions when built into a motor car. It should be noted, however, that excellent results have been obtained with a diameter of pinion 34 in the range of 25 mm. and with an axial dimension of pinion 34 together with its bosses 35, i.e. with an overall height of housing 30 taken in a direction vertical to the inner door panel 44, in the range of 16 mm. while the outer diameter of the tubular guide 26 may be 6 mm. or less. Therefore, the space necessary for positioning the guide 26 parallel to the path of the window pane and for mounting the housing 30 adjacent the lower end of said path is reduced to a minimum, while the motor 42 may be arranged and fixed to the inner door panel 44 at any desired position spaced from housing 30 and from the guided cable length 26, according to the space available. The second cable length 40 may be curved and of suitable length for transmitting the rotary driving force from the motor 42 to the pinion 34.

It will be appreciated that in an operating device for a sliding window according to the invention the housing 30 can be mounted in any desired angular position adjacent the lower end of the path of the sliding window. Because of the minimum of space required by the housing in a direction perpendicular to the plane of the inner door panel 44, there will always be sufficient room to position the flat housing near the lower end of window travel, thereby minimizing the overall length of tubular guide 26 wherein friction losses may occur when cable 28 is shifted axially. The position of motor 42 on the other hand may be chosen according to the space available in any type of car, whereby a possible greater length of the second cable 40 will not cause increase of friction since no guide is required for this second cable. However, the second cable, which transmits the motor torque to the pinion 34 in the manner of a flexible shaft on the one hand and in the manner of a worm on the other hand, may be supported from the door panel 44 at one point or the other of its length by conventional means, for instance bifurcated brackets or the like, by tubular pieces of comparatively wide cross section, if desired.

Though the motor 42 may be a commercial small electric motor as commonly used for operating windshield wipers or the like, it is of special advantage to have the electric motor 42 constructed with a flat rectangular cross section, as may be seen from FIG. 9. Here motor 42 is shown fixed by brackets 54 to the inner door panel 44.

In FIGS. 4 and 5 the arrangement of the regulator mechanism for a sliding window according to FIG. 3 be-

tween the inner and the outer door panel 44 and 20, respectively, is shown to require a minimum of space below the path of window travel; FIG. 4 showing the arrangement and shape of a tubular guide for a plane window and FIG. 5 for a longitudinally curved window, respectively. Though in both figures the position of motor 42 is shown to be the same, it will be appreciated that the motor 42 may be mounted in a different position according to the space available, because the second cable length 40 acting as a flexible shaft renders the position of the motor 42 independent on the position of the housing 30. Therefore, the housing may be arranged near the lower end of the window path as desirable to reduce friction losses, while the motor may take any desired position.

The embodiment according to FIG. 10 differs from the embodiment according to FIG. 3 by the position of housing 60 and motor 62. As will be seen from the drawing, the housing 60 is positioned below and adjacent the lower end of the path of the sliding window, while the electric motor 62 is positioned in a greater distance and actually in the region below the triangular window 22, i.e. spaced from that part of the automobile door in which the sliding window pane 7 is moving. This arrangement is especially advantageous in curved automobile doors with little space between the inner door panel and the window path. With such an arrangement the installation of a power operated window regulator will be possible even in a car door where most unfavorable conditions are encountered.

From the foregoing it is made clear, that in the simplest embodiment the power operated window regulating mechanism according to this invention may comprise a pinion meshing with two pieces of cable consisting of one or several coiled strands, one piece of cable being axially movable for operating the window, the other being connected to a motor and being mounted for rotation. It will be understood that this device is very inexpensive to manufacture and needs very little space for accommodation. It has the added advantage that the motor may be mounted at any desired place and independent on the position of the pinion.

While specific embodiments of the invention have been shown and described in detail to illustrate the application of the invention principles, it will be understood that the invention may be embodied otherwise without departing from such principles.

What is claimed is:

1. A power operated regulating mechanism for selectively raising and lowering a sliding vehicle window, comprising, in combination, a flat housing secured to the vehicle substantially below said window, a planar pinion rotatably mounted in said housing, a first and a second length of substantially identical threaded flexible cable meshing with said pinion in respective angularly spaced positions but substantially within the plane of said pinion, means for axially guiding said first length of cable through said housing, means for rotatably mounting said second length of cable at one end portion within said housing, means for securing said first length of cable to the lower edge of said window, tubular guide means secured to said vehicle for guiding said first length of cable within said housing and also between the latter and said window along a path substantially parallel to the sliding path of said window, a reversible electric motor mounted on said vehicle in a position spaced from said housing, and means for operatively connecting said motor to the other end portion of said second length of cable for rotation thereof, whereby said pinion will be rotated upon rotation of said second length of cable, thereby causing axial movement of said first length of cable and movement of said window along said sliding path.

5 2. A regulating mechanism according to claim 1, wherein said housing has respective first and second passages therein for said first and second lengths of cable, said first passage constituting said guiding means and forming part of said tubular guide means, said second length of cable constituting the driving element and said first length of cable the driven element with respect to said pinion during the raising and respective lowering of said window upon energization of said motor.

10 3. A regulating mechanism according to claim 1, wherein said connecting means includes a coupling between a driving shaft of said motor and said second length of cable in the form of a block of elastic material fixed to said one end of the second length of cable, a bushing secured to said block and having a bore to receive the free end of said motor shaft, and means for preventing relative rotational movement between said bushing and said motor shaft end.

15 4. A regulating mechanism according to claim 1, wherein said tubular guide means is longitudinally slotted, and said securing means includes a bracket between said first length of the cable and said lower window edge, and protruding through the slot of said tubular guide means, said bracket setting apart said path of the first length of cable from said sliding path of the window.

20 5. A power operated regulating mechanism for raising by positive pushing action and alternately for lowering by opposite action a sliding vehicle window, comprising, in combination, a housing secured to the vehicle substantially

25 below said window, a first flexible cable connected at its upper end to said window and having at an intermediate portion a worm-like profile providing first gear engagement means, an upper sleeve above said housing and a substantially aligned lower sleeve below said housing, for axially guiding the respective upper and lower end portions of said first cable in the window sliding direction, a passage through said housing for said first cable substantially aligned and coextensive with said sleeves so as to provide continuous axial guidance for said intermediate and said end portions of the first cable, a planar gear rotatably secured within said housing and having a single circumferential row of teeth, a reversible electric motor spaced apart from said housing, said first cable and said sleeves, a second flexible cable substantially identical with said first flexible cable, being connected at one end to the shaft of said motor and having at least at an intermediate portion a worm-like profile providing second gear engagement means substantially identical with said first gear engagement means, said gear being intermediate and substantially coplanar with said first and said second cables, said row of teeth being simultaneously and tangentially engaged by said first and said second gear engagement means, the latter being angularly spaced apart along said row of teeth, said second cable extending from said motor into said housing to act as driving means with respect to said gear while said first cable acts as driven means, and means for rotatably supporting said second cable within said housing.
